(57) **CLAIM**

The ornamental design for a bench back, as shown and described.

DESCRIPTION

FIG. 1 is a perspective view of a first embodiment of the bench back showing my design.

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof;

FIG. 8 is a front view of a second embodiment of the bench back having seven slats;

FIG. 9 is a front view of a third embodiment of the bench back having five slats; and,

FIG. 10 is a front view of a fourth embodiment of the bench back having three slats.

The features presented in broken lines are for environmental purposes only and form no part of the claimed design.
